ATTORNEY.

UNITED STATES PATENT OFFICE.

DUNCAN C. HOOKER, OF FARMINGTON, CONNECTICUT, ASSIGNOR TO THE JOHNS-PRATT COMPANY, OF HARTFORD, CONNECTICUT, A CORPORATION OF CONNECTICUT.

FUSE-BLOCK.

1,234,544.

Specification of Letters Patent.

Patented July 24, 1917.

Application filed July 1, 1916. Serial No. 107,018.

To all whom it may concern:

Be it known that I, DUNCAN C. HOOKER, a citizen of the United States, residing at Farmington, in the county of Hartford and 5 State of Connecticut, have invented a new and useful Improvement in Fuse-Blocks, of which the following is a specification.

This invention relates to the conductors on a fuse block which are employed for electrically connecting the wire terminals with 10 the fuse terminals.

The object of the invention is to provide a fuse block with very simple and cheap conducting means which are easily manipulated 15 and which will efficiently connect the wire terminals and the fuse terminals.

The invention is particularly adapted for fuse blocks designed to receive fuses of relatively large capacity, for instance, fuses of 20 100 ampere and upward rated capacity, which fuses at the present time commonly have knife blade terminals.

Figure 1 of the accompanying drawings shows a side elevation of a fuse block having 25 spring clips for receiving fuse terminals of the knife blade type and provided with socketed lugs for receiving the wire terminals, which clips and lugs are constructed and connected in accordance with the 30 present invention. Fig. 2 shows a plan of the same. Fig. 3 shows a vertical transverse section taken on the plane indicated by the dotted line 3—3 on Fig. 2 and looking in the direction indicated by the arrows. Fig. 4 is 35 a perspective view showing one end of the insulating base with one of the metal wire lugs placed thereon.

The base 1 of the block is preferably a 40 piece of porcelain, slate or similar insulating material. Projecting upwardly from the base near each end are two screws, bolts or threaded studs 2. These screws are desirably staggered and are fixed so they will not turn. The bottoms 3 of the spring clips 45 4, which are designed to receive knife blade terminals of a fuse, have perforations so that they may be set down upon the upper face of the base with the screws projecting upwardly into them. After the spring clips 50 have been placed on the base over the screws nuts 5 are turned on the screws.

Before the nuts are turned down tightly the flattened ends 6 of the socketed wire terminal lugs 7 are slipped in between the

upper surface of the base and the under surface of the bottom of the spring clips, slots 8 being desirably cut diagonally in the flat ends of the wire lugs to permit this. After the wire lugs have been placed in position the nuts are turned down on the screws so as to tightly clamp the clips down on the lugs and secure the parts together. 55

When it is desired to fasten wire terminals in the sockets of the lugs the nuts are loosened and the lugs withdrawn. After 60 the wire terminals have been soldered into the lug sockets the flat portions of the lugs are slipped onto the block beneath the clips and the nuts tightened. These devices may be packed in a small space for shipment by 65 loosening the nuts and reversing the lugs so that they will occupy the positions illustrated by the dotted lines in Fig. 1. The lugs may be cast or they may, as shown, be formed of sections of tubing with portions 70 flattened. There are a minimum number of conducting parts to this block and maximum contact is provided between the lugs to which the wire terminals are secured and the spring clips which are designed to receive 75 the knife blade terminals of the fuse, thus insuring efficiency of action at a low cost.

The invention claimed is:

1. A fuse block having a base, spring clips with screw openings mounted on the base, 85 wire lugs with flattened ends provided with oblique slots in electrical contact with the spring clips, and screws passing through the openings in the clips and slots in the lugs and into base for clamping the clips and the 90 lugs together and to the base.

2. A fuse block having an insulating base, spring clips with perforations in their bottoms mounted on the base, socketed wire lugs with slotted flat portions located between the upper surface of the base and the bottoms of the spring clips, and screws passing through the base, the slots in the flattened portions of the lugs and the perforations in the bottoms of the clips for clamping the clips down upon the flat portions of the wire lugs and holding the parts together upon the base. 95 100

3. A fuse block having an insulating base, spring clips with openings through their bottoms and sides mounted upon the base, wire lugs with slotted portions located between the upper surface of the base and the 105

bottoms of the spring clips, screws projecting upwardly from the base through the slots in the lugs and openings in the bottoms of the spring clips, and nuts turning upon the screws and exposed through the openings in the sides of the spring clips for clamping the clips down upon the wire lugs.

4. A fuse block having a base, spring clips mounted on the base, screws projecting upwardly from the base into the spring clips, wire lugs with flattened sections provided with oblique slots located on the base beneath the bottoms of the spring clips, and nuts turning on the screws for clamping the

clips down upon the flattened portions of 15 the wire lugs.

5. A fuse block having an insulating base, two screws projecting upwardly near each end of the base, spring clips located on the upper surface of the base over the screws, 20 socketed wire lugs with flattened ends having oblique slots inserted between the base and the spring clips, and nuts turning on the screws for clamping the clips down upon the flattened portions of the wire lugs, or releasing the flattened portions of the wire lugs from between the base and the clips. 25

DUNCAN C. HOOKER.
